COMPARTMENT DEVICE

Harry S. Frank, New York, N. Y.

Application January 8, 1934, Serial No. 705,704

5 Claims. (Cl. 229—15)

This invention relates to compartment forming devices, and its main objects are to provide a simple, relatively inexpensive, easily connectible structure, adapted to either divide into or form compartments of existing drawers, shelves, closets, etc. or to serve itself as a receptacle, which may be pre-fabricated and easily shipped and stored in its collapsed state, and the process of making and assembling it.

Another object of this invention is to provide, for the purpose of facilitating quantity production, standardized strips of material, equipped with uniformly arranged or evenly distributed fastener receiving means, which strips may be fabricated in any length and subsequently cut to desired sizes so as to form either marginal or side members, or partition members.

Another object of my invention is to so finish or cover the interior or "to-be-exposed" surfaces of the device, as to obscure the connections between and the means of connecting the different parts.

Another object of this invention is to so construct the pre-fabricated parts of my device as to facilitate the insertion or placement of the assembled article wherever it is to be used.

Another of the objects of this invention resides in producing standardized fastening means applicable to any of the strip-formed parts from which marginal or partition members are made.

The foregoing and a great many further objects of my invention will become more fully apparent from the following description of the accompanying drawing, forming part of my disclosure, which drawing is primarily intended to elucidate the principle of my invention, not, however, designed to limit the same to the actual structure shown, and in which:

Fig. 1 is a perspective illustration of my assembled device in one of the many possible forms,

Fig. 2 is a cross-sectional view taken on lines 2—2 of Fig. 1,

Fig. 3 is a cross-sectional view taken on lines 3—3 of Fig. 1,

Fig. 4 illustrates several elements of the corner fastening means employed in my device,

Fig. 5 is an elevation of a portion of a partition member, one part of its front section being left off,

Fig. 6 is a right-hand end view thereof,

Fig. 7 is a top view of my partition member, its hinge connection at the upper edge being partially broken off, and

Fig. 8 is a partial cross-sectional view, similar to

that shown in Fig. 2, but of a modified construction.

Referring now specifically to the drawing, numeral 10 denotes a base, back or bottom of my device, depending upon its desired application. Hinged to the edges of the base at 11 in any convenient manner are marginal or side members 12, while a plurality of partition members of various sizes and arrangement are located within said side or marginal members.

In Fig. 1 is illustrated, for explanatory purposes only, a suitable arrangement for an existing drawer, in which I employ two through-partition members 13 and 14, dividing the structure into three main compartments, which latter are again sub-divided into smaller units. In the front main compartment two partitions 15 and 16 are shown, the middle main compartment is subdivided by partitions 17 and 18, and the rear compartment possesses three partitions 19 dividing it into four small compartments.

The basic material employed in the manufacture of the marginal or side members and of the partition members consists of strips of uniform width, provided with evenly spaced fastener attaching or receiving means, such as the slots indicated at 20, arranged in two or more parallel rows. The strip material may be fabricated in any length and cut to desired sizes. Any suitable material may be employed such as cardboard, fiber, laminated wood, bakelite, sheet metal or any other sheeting applicable for similar manufacture.

Similarly, the base material may be prepared from suitable sheets and perforated for receiving desired fastening means. Such perforations are indicated at 21 and are shown to be in the shape of crosses, although any other design suitable for the work may be employed. This applies equally to the perforations provided in the side and partition material.

In Figs. 2 and 3 typical cross sections of the marginal members 12 are illustrated, which are preferably made of a single ply of material. At the upper edge of these side members I provide a bead 22, intended to serve as spacer for the purpose of preventing the fastening means, (holding the side members together at their corners and other fastening means whereby the partition members are attached to the sides) from interfering with the insertion of the device into the drawer and from damaging the inner drawer surfaces.

For a similar purpose the marginal members may be made of a double ply, as indicated in the modified form of Fig. 8, where instead of bead 22

Assembly operation

and outer flap 22' is hinged at 23 to marginal member 12. This flap is intended to cover the fastening means completely and to facilitate the insertion of the device into a drawer. However, 5 this flap may also serve for finishing the exterior of the sides so that the device may be used as an independent container.

The construction of the partition members 10 preferably consists of two adjacent plies of strips hinged together at their upper edges. A typical arrangement is illustrated in Figures 5, 6 and 7 consisting of strips 24 and 25, both provided with the aforesaid perforations 20, and hinged together at their upper edges, as indicated at 26.

15 The assembly of the different parts of my device is accomplished by means of suitable fastening means, such as illustrated in Figures 1, 3, 4, 5, 6 and 7. The marginal or side members are united at their corners by means of narrow strips 27 20 provided with a pair of slots 28 and an end slot 29 (see Fig. 4). Yoke-shaped elements 30 are 25 inserted with their prongs 31 through the two end slots 20 of the marginal members 12. One of the elements engages with its prongs slots 28 of strip 27 (see Fig. 3), while the corresponding element engages attaching plate 32 which is also provided with slots 33 adapted to receive prongs 31 of that corresponding element. Between slots 33 of the plate, a lip 34 is pressed out and is adapted 30 to engage slot 29 of strip 27. Prongs or projections 31, after having passed through sheets 12 and the apertures 28 and 32 of the strip and plate, respectively, are bent down, thus locking the two last mentioned elements in place. By bending 35 strip 27 on bending line 35 (Fig. 4) and swinging it about the corner-forming edges of the abutting ends of two members 12, slot 29 of strip 27 is slipped over lip 34 which is then bent over and holds strip 27 in place. In this manner all four 40 corners of the device are held together at top and bottom and form substantial uniting means and reinforcements, which however may be disconnected whenever desired.

45 The method of attaching and holding the partition members in place is somewhat different. Yokes 30', similar to elements 30, are employed. Their prongs 31' are passed through perforations 20 of the partition members from without to within, as clearly seen in Figures 6 and 7, and 50 engage end-attaching elements 36, which are provided with slots 37, corresponding in arrangement and distance from one another to that of slots 20 in strips 12'. The body portions of elements 36 are relatively broad and terminate in outer reduced attaching tongs 38. The latter 55 are intended to pass through any one of the slots or perforations 20 of either the wall or marginal members, or of other partition members, and they are preferably so arranged that always two 60 tongs of two adjacent plies may be passed through the perforations together and then bent over, as may be clearly observed at the front and right hand side walls in Fig. 1.

65 Where long partitions are employed, such as main partitions 13 and 14, I preferably secure them at one or more places to the base member, as illustrated in the middle compartment at A. The prongs 31 of fastener element 30 are passed 70 through perforations in one of the partition plies and through slots 37 of an end-attaching element 36, and are bent over in the usual way. The tong of element 38 is passed through one of the cross-perforations in the base 75 and fastened by likewise bending it over.

5 In inter-connecting the shorter partitions with the main partitions, I proceed in a certain manner. Assuming that after fastening two of the marginal members in place, say the front and left-hand members, I now attach partitions 15 and 16 to the front member. Then I secure these partitions to the front flap of main partition 13 by first lifting up the rear flap. Now partitions 17 and 18 are secured to the still elevated or partially opened rear flap of main partition 13. Now partitions 17 and 18 are secured to the front flap of main partition 14, and to its rear flap short partitions 19 are attached. Both flaps of all short partitions 15, 16, 17, 18 and 19 are held against one another due to the fact that always both tongs of two adjacent attaching elements 36 are slipped through and secured to one of the slots 20 of either the marginal members or the flaps of the long partitions.

10 After attachment of all short partitions to the main partitions in the manner outlined above, the flaps of the main partitions are brought together and their end-attaching means are aligned so as to register with their intended slots in the marginal members. The adjacent tongs of the fastening elements at one end of the long partitions are then slipped first through the slots of one of the marginal members, say the left-hand member, and bent over. Now the prongs of short partitions 19 are secured to the rear marginal member, and finally the right hand prongs of the long or main partitions are fastened to the right-hand marginal member.

15 When all partitions are thus assembled and the main partitions secured in places to the base, as at A, the corner-forming fastening means of the marginal members are attached, and the device is ready for use.

20 It will be observed from the drawing that all exposed surfaces of the base, the marginal and partition members are finished or covered to present a pleasing appearance. Such finish is applied after the attachment of all fastening elements, particularly the yoke-shaped members 30 or 30'. The finish may be in the form of lacquer, paint, varnish or a covering material such as leather, cloth, paper and the like, and if covering material is used, it serves also in forming connections between two strips in the manner shown 25 in Figs. 6 and 8.

25 When finishing or covering material is used, it is so attached to the future-to-be-exposed surfaces that perforations 20 may be easily discerned and an incision made in the material for facilitating the insertions of attaching prongs 38 of the partitions. In the drawing the covering material is indicated at C, and I found it advantageous to employ imitation suède for this purpose, altho any other finish may prove just as 30 satisfactory.

35 In developing the article, I had in mind the foremost prerequisite of success as to manufacture and salability, that is inexpensiveness, simplicity of production, ability of pre-fabrication, simplicity of assembly and capability of shipping and storing the article in a knocked-down, space-saving manner. Accordingly, the material employed may be of an inexpensive nature, requiring very little handling to provide it with the necessary perforations, fastening means and finishing material. The marginal and partition members may be pre-fabricated, as well as the base, shipped and stored flat, and cut to desired 40 45 50 55 60 65 70 75 75

sizes and assembled at its place of immediate future use.

These advantages make it possible for the retailer to fill any specific order immediately without requiring the help of the manufacturer. If, for instance, a drawer is to be equipped with my device, all that is required of the customer is to give the inside dimensions of the drawer and to indicate his wishes as to the approximate arrangement of the compartments. The same procedure applies to shelves, closets or other spaces intended to be sub-divided.

From the foregoing it becomes quite evident that my invention has universal uses and may be produced in large quantities and in different sizes, since its process of manufacture remains the same. It is obvious also that it may be produced from various materials best suited for specific uses and that the fastening means and their attachment may have to be altered in order to withstand use and abuse. Consequently, while I have shown specific forms of my invention, it is understood that they are not intended to limit my invention to the actual illustrations and details and that changes and improvements may be incorporated therein without departing from its broad scope, as defined in the annexed claims.

I claim:

1. A compartment device, comprising in combination, a base member, marginal or side members hingedly connected therewith and provided with uniformly distributed fastener receiving means arranged in double rows, corner fastener means in engagement with some of said receiving means of both rows and adapted to unite said marginal members at their corners, a plurality of partition members disposed within said marginal members and provided with two rows of uniformly distributed fastener element receiving means, fastener elements associated with some of these element receiving means of both rows and disposed at the ends of said partition members, and engaging some of the fastener receiving means of both rows of said marginal members and some of the element receiving means of both rows of some of the partition members.

2. A collapsible compartment forming device, comprising in combination, a base or bottom member provided with fastener receiving means,

marginal or side members hingedly associated with the edges of said base member, a plurality of uniformly distributed fastener receiving means provided with said marginal members and arranged in two parallel rows, a plurality of partition members adapted to be associated with one another and with said marginal members and said base member, and provided with two corresponding, parallel rows of uniformly distributed fastening-element receiving means, removable and exchangeable, uniform corner fasteners associated in pairs with the ends of said marginal members at said fastener receiving means, a plurality of uniform and exchangeable fastening elements secured in pairs at the ends, and at certain intervals at the bottom edges of said partition members and adapted to engage some partition and marginal members, and the base member, respectively.

3. In a collapsible compartment forming device, as set forth in claim 2, said marginal members provided with means for rendering said corner fasteners and some of said fastening elements, in engagement with said marginal members, unobstructive and for facilitating the placement of the device wherever intended.

4. In a device of the class described, marginal and partition members adapted to be interconnected with one another, each of said members forming portions of strips provided with uniformly distributed fastener receiving means, said marginal members provided at their surfaces to be exposed to view, with a finish or covering, said partition members comprising a double ply of hinged strips having at their surfaces to be exposed to view an outer finish or covering, and a plurality of fastening means secured in said receiving means of both kind of members and so arranged as to be obscured by said finish or covering, said fastening means adapted to facilitate connecting said members in forming compartments therefrom.

5. In a device as set forth in claim 4, said fastening means comprising substantially yoke-shaped elements adapted to pass through the strip material and perforated attaching elements engaged and held by said former elements.

HARRY S. FRANK.
